US0D1087022S

(12) **United States Design Patent** (10) Patent No.: **US D1,087,022 S**
(45) Date of Patent: ** Aug. 5, 2025

(54) **FREQUENCY CONVERTER**

(71) Applicant: **Danfoss Power Electronics A/S**,
Gråsten (DK)

(72) Inventor: **Michael Sørensen**, Gråsten (DK)

(73) Assignee: **DANFOSS POWER ELECTRONICS**
A/S, Grasten (DK)

(**) Term: **15 Years**

(21) Appl. No.: **29/907,955**

(22) Filed: **Jan. 10, 2024**

(57) **CLAIM**

The ornamental design for a frequency converter substantially as shown and described.

DESCRIPTION

FIG. 1 is a front, right side and top perspective view of a frequency converter comprising a new, original and ornamental design;

FIG. 2 is a front view thereof;

FIG. 3 is a back view thereof;

FIG. 4 is a top view thereof;

FIG. 5 is a bottom view thereof;

FIG. 6 is a left view thereof; and,

FIG. 7 is a right view thereof.

The broken lines depict portions of the frequency converter that form no part of the claimed design.

1 Claim, 7 Drawing Sheets
